United States Patent

Des. 242,435
Patented Nov. 23, 1976

242,435

CLOCK

James A. Warner, 20 Elmore St.,
Pittsburgh, Pa. 15219

Filed Sept. 2, 1975, Ser. No. 609,602

Term of patent 14 years

Int. Cl. D10—01

U.S. Cl. D10—21

Fig. 1

Fig. 2

FIG. 1 is a front elevational view of a clock showing my new design, the rear being substantially plain and unornamented;

FIG. 2 is a right side elevational view thereof, the left side being a mirror image thereto.

I claim:

The ornamental design for a clock, substantially as shown and described.
